FILTERS

Harry R. Litchfield and Jacob J. Schneider, Brooklyn, N.Y., assignors to themselves jointly
Filed Oct. 24, 1958, Ser. No. 769,472
10 Claims. (Cl. 131—10)

This invention relates to filters and more specifically to tobacco smoke filters, and still more specifically to cigarette filters.

This invention also relates to a method of selectively filtering components from smoke during the smoking of tobacco.

Known to us is the procedure in ventilating rooms and in smoking, specifically of cigarettes, to provide smoke filters which, within limits, mechanically absorb such air suspended materials as dust, pollens and which physically absorb suspended products of combustion present in smoke constituents.

Known to us also are the various claims made of the selective effectiveness of absorbents and adsorbents, by means of which mechanical removal of products of combustion, such as tars, from cigarette smoke or tobacco smoke, has been achieved, while leaving the effluent products to retain some components which make tobacco smoking, pipe, cigarette and cigar, pleasurable, thus pointing to the selection in the prior art of a filter which is only partially effective in separating the products of combustion from the gaseous vehicle in which these ingredients are entrained. Such filters must result in sacrifice of the pleasure of smoke taste to filtering effectiveness, without due consideration to the fact that the effluent still of necessity contains objectionable components by reason of the fact that in the use of mere mechanical filtering, whether by absorption or adsorption, it has not been established to which of the ingredients of the effluent, the filter shall be selective or effective. Obviously, it must be concluded that mere mechanical filters, no matter how efficient, are therefore prone to defeat the very basis for smoking pleasure because volatile components or gasiform materials are the least likely to be mechanically withheld by the filters from the smoke inhaled by the smoker.

Recognition of the fact that the use of indiscriminate adsorbent filters of volatile components of tobacco smoke would be most likely to detract from the pleasure derived from smoking, as both harmful and harmless tobacco smoke components carried by the effluent would thereby be withheld in being drawn through the adsorbent type of filter, it is evident that efficiency of filtering is not the answer to the problem.

We have discovered that the harmful by-products of tobacco smoking, particularly those which are of the difficultly filterable components of tobacco smoke, such as carbon monoxide, nicotine, aldehydes, pyridine and other polycyclic hydrocarbons, which appear to influence bronchogenic malignancy or are of contributory nature to coronary disease and carcinoma, have an avid compatible relationship to the human tissue to which these gaseous by-products of tobacco smoke are exposed.

We have further determined that pathologically there is great similarity between the tissue of humans and animals in the compatible relationship of the tissue to the objectionable, noxious by products of smoke, particularly tobacco smoke.

In an effort to stimulate or accelerate the interaction between the gaseous components before reaching the human tissue, whereby to minimize the pathogenesis resulting from inhaling air charged with tobacco smoke or other components by human beings, we have devised a filter which results in exposing the human to greatly reduced quantities of the entrained noxious components during

2

smoking. We have devised as a filter for the noxious materials ordinarily inhaled by the human during tobacco smoking, or for use during air purifying, a large surface exposure of pulverized lung tissue, thereby eliminating or 5 greatly reducing the hazards of inhaling smoke. Specifically, we have incorporated fragments of lung tissue of calf, fowl, sheep or hog, preferably in powdered or pulverized form, as a filter barrier to materials entrained by smoke and thereby separating by adsorption and absorption, the products which are destructive or injurious to the 10 respiratory and vascular systems, to leave a smoke which may be inhaled which is greatly, if not entirely, cleared of its noxious, pathogenetic elements.

Still more specifically, we have incorporated in filters 15 for cigarettes or like smoking appliances, a combined mechanical and gasiform filter barrier to the tobacco smoke stream, whereby the smoke effluent thereof which the human is exposed by inhaling, is rendered less hazardous by the combination of a barrier of pulverized lung powder, such as derived from calves, sheep or hogs or combinations thereof, which filter barrier appears selectively to concentrate some of the noxious components of burning tobacco on the pulverized tissue, while providing an effluent having the factors contributing to the pleasures 20 of tobacco smoking.

To attain these objects and such further objects as may appear herein or be hereinafter pointed out, we make reference to the accompany drawing forming a part hereof, in which:

30 FIGURE 1 is a perspective view, partly in section, illustrating an embodiment of our invention;

FIGURE 2 is an exploded, magnified, perspective view of the components thereof;

FIGURE 3 is a longitudinal sectional view of another 35 embodiment of our invention;

FIGURE 4 is an exploded perspective view of the baffles employed in the embodiment shown in FIGURE 3.

Referring to the drawing, one embodiment of the 40 invention may consist of a smoking device consisting of a smoking segment 10 and a filtering segment 11. These segments may constitute integrated portions or detachable portions whereby, upon attaching the smoking segment 10 to the filtering segment 11, the latter may be reused.

45 In the illustration, by way of example, the smoking segment 10 comprises the usual cigarette components of a cylindrical section of paper 12, such as rice paper, into which a charge of tobacco 13 may be compacted, having a sleeve 14 of less permeable and preferably stiffer paper 50 to withstand the pressure and moisture of the lips, which is recognized as usually found in filter cigarettes, and in the nature of a cigarette holder.

55 Into the cylindrical section thus described and constituting the filtering section 11, we introduce a mechanical filter block 15, a charge holder 16, a baffle plate 17 and a second block filter 18. The block filters 15 and 18 are designed mechanically to filter the products of combustion from smoking tobacco 13, and may constitute a roll of paper convoluted to provide a plurality 60 of fine, longitudinally extended passages.

The baffle 17, which may be positioned adjacent one of the rims 19 and 20, consists of an impervious piece of paper having a non-symmetrically located slot 21, in which event, if a similar baffle is positioned adjacent the 65 rim 20, the corresponding slot 21 is located in a diametrically opposite position.

The charge holder 16, in the embodiment illustrated, is constructed adjacent the medial portion 22, further to carry out the objective of not stratifying the gaseous 70 product drawn in during smoking through the block 15, and to endeavor to secure an attenuated path of flow, for

purposes which will appear more clearly as this description proceeds.

The charge holder is filled with a gasiform barrier 23, preferably in pulverized form. The barrier material which carries out the objective of this invention constitutes lung tissue of various animals, specifically, the lungs of calves, beef, sheep, hogs being examples. While dried sections of such tissue may be employed to constitute the barrier within the charge holder 16, we prefer to utilize the lung tissue in powdered form.

We give the following as an example of such material employing calves' lung.

Example I

Calves' lungs are minced in the frozen state and then dried under vacuum with a circulating water temperature of about 150° F. The moisture is removed until the residuum has a moisture content of less than 5%, about 3 to 4% being suitable. The tissue is thereupon ground so that about 100% will pass a 20 mesh screen. Such pulverized barrier material is then ready to be packed within the charge holder, under compaction just sufficient to be retained without unduly obstructing the flow of gasiform material, as experienced in normal smoking.

Another example for preparing the barrier which may be retained within the charge holder 16 is as follows:

Example II

The hot lungs from beef and sheep are ground through a grinding machine having grinding apertures of about $\frac{1}{8}$ inch diameter. The ground lungs are then placed in a vacuum drier, agitated under reduced pressure of about 3 mm. of mercury. The drier is water agitated, and held at approximately 130° F. The moisture content is reduced under such vacuum drying from about 85% moisture to about 3 or 4%, although up to 5% may be employed.

The dried lung material is then ground further so that approximately 100% may pass through a 60 mesh screen, although a range of from 20 to 60 mesh may be employed.

A histological examination of the lung powder is as follows:

The tissue block shows numerous varying sized bits of tissue, among which are recognizable cartilage, alveola, blood vessels and septal elements.

In use in a cigarette or in a cigarette holder, the confining cylinder is filled with the dried lung material without compaction. It is to be understood, however, if a more restricted draft is desired, it may be compacted to a greater degree.

We attribute the desirable features to carry out the objective of the filtering action to the presence of predominant alveolar elements, although there are recognizable cartilage, blood vessel and septal elements. The lung tissue, particularly the pulverized lung tissue which comes from calves, fowl, sheep or hogs or combinations of the same, appears selectively to concentrate the noxious components of burning tobacco because of what we believe is the same compatible relationship of the human tissue to the objectionable, noxious by-products when inhaled by the human being.

Thus, in accordance with our construction, we provide a filter which effectively subtracts from the smoke those of the noxious components which have an avid compatible relationship to the human tissue to which the gaseous by-products of tobacco smoke are exposed, thereby effectively minimizing the noxious components of tobacco smoke which reach the tissue of the human inhaled by the human being.

Another embodiment of the construction described is exemplified in FIGURES 3 and 4 wherein a filter holder 14a may be associated with the cigarette

either as a holder for the same or as a consolidated, disposable element. In this construction, filter blocks 15a and 18a are positioned within the holder 14a to support therebetween a barrier charge 23a, 23b, separated by baffles 17a, 17b, 17c, carrying staggered apertures 21a, 21b, 21c in planes to assure a sinuous path of smoke from the blocks 15a to the block 18a. In other respects, the carrier chambers 23a and 23b carry out the objective heretofore exemplified in connection with FIGURES 1 and 2.

While we have described and illustrated filters for smoking appliances in the form of cigarettes, it will be understood that the filtering relationship may have utility in numerous devices where filtering action may be found desirable, such as in air conditioning appliances or in ventilators for depollinating the air.

Other uses of the filtering component will readily suggest themselves from the description herein given, and our invention is to be construed within the scope of the appended claims.

Having thus described our invention and illustrated its use, what we claim as new and desire to secure by Letters Patent, is:

1. A filter component for the purposes described comprising the fragmented lung tissue of animals selected from the group consisting of fowl, calves, beef, sheep and hogs, the fragmented tissue having predominant recognizable alveolar cells.

2. A filter component for the purposes described comprising the fragmented lung tissue of animals selected from the group consisting of fowl, calves, beef, sheep and hogs, said tissue being in powdered form, the fragmented tissue having predominant recognizable alveolar cells.

3. A filter component for the purposes described comprising the fragmented lung tissue of animals selected from the group consisting of fowl, calves, beef, sheep and hogs, said tissue being in powdered form within a range where 100% passes through a 20 mesh screen, the fragmented tissue having predominant recognizable alveolar cells.

4. A filter component for the purposes described comprising the fragmented lung tissue of animals selected from the group consisting of fowl, calves, beef, sheep and hogs, said tissue being dried to a moisture content of from 3 to 5% and within a range where 100% passes through a 20 mesh screen and is retained on a 60 mesh screen, the fragmented tissue having predominant recognizable alveolar cells.

5. A tobacco smoking device having a filter element and containing a filter barrier comprising fragmented tissue of animals selected from the group consisting of calf lungs, beef lungs, fowl lungs, sheep lungs, hog lungs, the fragmented tissue having predominant recognizable alveolar cells.

6. A tobacco smoking device having a filter element and containing a filter barrier comprising fragmented tissue of animals selected from the group consisting of calf lungs, beef lungs, fowl lungs, sheep lungs, hog lungs, said tissue being in powdered form, the fragmented tissue having predominant recognizable alveolar cells.

7. A tobacco smoking device having a filter element and containing a filter barrier comprising fragmented tissue of animals selected from the group consisting of calf lungs, beef lungs, fowl lungs, sheep lungs, hog lungs, said tissue being in powdered form, within a range where 100% passes through a 20 mesh screen, the fragmented tissue having predominant recognizable alveolar cells.

8. A tobacco smoking device having a filter element and containing a filter barrier comprising fragmented tissue of animals selected from the group consisting of calf lungs, beef lungs, fowl lungs, sheep lungs, hog lungs, said

tissue being dried to a moisture content of from 3 to 5% and within a range where 100% passes through a 20 mesh screen and is retained on a 60 mesh screen, the fragmented tissue having predominant recognizable alveolar cells.

9. The method of filtering of noxious gaseous products from tobacco smoke by the step of passing smoke entraining said noxious gaseous products through fragmented, dried tissue of animals selected from the group consisting of fowl lungs, calf lungs, beef lungs, sheep lungs, hog lungs, the fragmented tissue having predominant recognizable alveolar cells.

10. A filter tip for cigarettes having a filter barrier comprising fragmented tissue particles taken from animal lungs consisting of calf lungs, beef lungs, fowl lungs, sheep lungs, hog lungs, the fragmented tissue having predominant recognizable alveolar cells.
